UNITED STATES PATENT OFFICE

WALTER S. MAYER, OF PHILADELPHIA, PENNSYLVANIA

ELECTRIC PLUG RECEPTACLE

Application filed February 1, 1922. Serial No. 533,450.

This invention is a plug receptacle having plural sockets, and its object, generally stated, is to produce an improved plural socket receptacle that is simple, sturdy and efficient, at reduced cost.

The invention is characterized, in its preferred form, by its insulating body (provided with plural sockets containing conducting shells and with a neck) that is 10 adapted to be readily molded; an insulating extension (provided with a conducting shell) having a reduced and recessed projecting part adapted to fit said neck; a conducting yoke disposed in the recessed neck; 15 contact screws or bolts extending through the body from the centres of the sockets therein into engagement with the yoke to hold the same in position; a conducting screw or bolt extending centrally through 20 the insulating extension into the yoke; conducting clips engaged between the insulating body and extension in contact with the shell on the extension, and conducting bolts or screws extending through the body eccentrically to their sockets to connect the shells 25 therein with the respective clips.

In the drawings, Fig. 1 is a top view of the insulating body with the insulating extension removed therefrom to show the recessed neck and the shoulders with the conducting parts therein; Fig. 2 is a part sectional view of the construction taken on the line 2^x—2^x of Fig. 1; Fig. 3 is a sectional view taken on the line 3^x—3^x of Fig. 2; Fig. 4 is a side view of the detached insulating extension; Fig. 5 is a view of the bottom of the extension; Fig. 6 is a perspective view of the conducting yoke detached; Fig. 7 is a top view similar to that shown in Fig. 1 in illustration of a modified construction of the body made in sections adapted to be joined on the line 2^x—2^x of Fig. 1, and Fig. 8 is a side view of the inner part of the section shown in Fig. 7.

As illustrated in the drawings, the receptacle comprises the insulating body 1 having therein the converging sockets 2 and thereon the neck or projection 3 together with the shoulders 4 and containing the recess 5. An insulating extension piece or

plug 6 is supported on the body 1 and is provided with the tongue 7 which fits in the part 3, this extension piece containing the recesses 8 which register with the shoulders 4. Conducting bolts or screws 9 are 55 passed through the holes 10 in the body 1, in line with the axes of the sockets 2 and engage the respective ends of a metal yoke 11 seated in the bottom of the recess 5.

A conducting bolt or screw 12 is passed 60 through the axial hole 13 in the extension 6 into engagement with the centre of the yoke.

Threaded conducting shells 14 in the respective sockets 2 have in their respective bottoms 15 the openings 16 through which project hubs 17 of the body 1, which hubs serve to position the shells and project the lamp contact heads of the bolts 9, passing therethrough, into the shell. Conducting bolts or screws 18 pass through the holes 19 in the body 1 and through the bottoms of the shells 14 to hold the latter in place and connect them electrically with a threaded metal shell 20 on the part 6, the shell 20 70 having the bottom 21 which rests on the shoulders 4 and the bottom aperture 22 through which the neck 3 projects and in which it fits. The bolts 18, which pass through the bottom of the shell 20, are engaged to angular metal clips 23 supported thereby and disposed in the recesses 8, the bottom having the projections 24 engaged in the reentrant angles of the clips. 75

The integral body 1, illustrated in Figs. 1, 2 and 3, may be made in sections by dividing it on the line 2^x—2^x of Fig. 1 with the production of complementary parts, one of which is illustrated in Figs. 7 and 8, such parts 1' being clamped together by bolting through a hole 25. Such a construction is adopted to be molded simply by simple apparatus and assembled by few operations. 80

In my improvements, as will be now seen, the connections are simple and made directly by straight bolts. Screw pressure is thereby obtained for securing the desired binding of the parts together and the consequent excellency of contact. 95

If desired, changes and additions may be 100

made in the construction, as for instance by the use of insulating washers (not shown) between the heads of the bolts 9 and the bottoms of the shells 14 so as to cover the heads 5 of the bolts 18, without departing from my invention.

Having described my invention, I claim:

1. A plug receptacle having an insulating body containing a plurality of sockets, contact screws passing through said body with heads disposed centrally in the respective sockets, a conducting member engaged by said screws, a plug comprising an insulating part and a conducting shell thereon having 15 a flange disposed between said body and plug, a contact screw passing through said part into engagement with said member, conducting shells in the respective sockets and electrically separated from said contact 20 screws, and means for electrically connecting the shells in said sockets with the shell on said insulating part, said means including conducting screws normal to the surface of and engaging the bottoms of the shells in 25 said sockets and passing in a straight line through said body and the flange of said shell.

2. A plug receptacle having an insulating body containing a plurality of sockets and 30 a recess, an insulating member having a part disposed in said recess, a conducting member in said recess, contact screws engaging said conducting member and extending through said body to the respective sockets 35 therein, a contact screw engaging said conducting member and extending through said insulating member, conducting shells in said sockets and on said insulating member respectively, detachable angular conducting 40 clips electrically connected with the shell on said insulating member and supported by said body, and conducting screws passing through said body and engaging said shells and clips to secure them to said body.

45 3. A plug receptacle having an insulating body provided with a plurality of sockets, a recess, and shoulders, in combination with an insulating plug having a tongue disposed in said recess and recesses registering with 50 said shoulders, a conducting yoke supported in the recess in said body, contact screws passing from said sockets through said body into engagement with said yoke, a conducting screw passing through said plug into 55 engagement with said yoke, a conducting shell on said body, said shell having a bottom disposed between said plug and body, conducting clips disposed in the recesses of said plug and engaging the bottom of said 60 shell, conducting shells in said sockets in insulated relation to said screws, and conducting binding members connecting said shells last named with said clips.

65 4. A plug receptacle comprising an insulating body containing angularly disposed

sockets having bases integral with said body, a detachable plug, a conducting member housed between said plug and body and secured to the latter by bolts passing through said socket bases into said sockets, a shell 70 on said plug and having inturned parts thereon disposed between said plug and body and secured to the latter by bolts passing through said inturned parts through said socket bases into said sockets, conducting shells secured in said sockets by the engagement therewith of bolts aforesaid, and a bolt passing through said plug into said first named conducting member and securing said plug to said body.

In testimony whereof I have hereunto set my name this 26th day of January, 1922.

WALTER S. MAYER.
